INVENTOR.

UNITED STATES PATENT OFFICE.

LARS G. HEDLUND, OF ROTHsay, MINNESOTA.

CAR-COUPLING.

SPECIFICATION forming part of Letters Patent No. 286,001, dated October 2, 1883.

Application filed August 2, 1883. (No model.)

To all whom it may concern:

Be it known that I, LARS G. HEDLUND, a citizen of the United States, residing at Rothsay, in the county of Wilkin and State of Minnesota, have invented certain new and useful Improvements in Car-Couplings; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of two coupled draw-heads of my improved car-coupling. Fig. 2 is a side view of the draw-head provided with the coupling mechanism uncoupled. Fig. 3 is a similar view of the same, ready for 15 coupling. Fig. 4 is a vertical longitudinal section of the two draw-heads; and Fig. 5 is a perspective detail view of the mechanism for holding the coupling-bolt.

Similar letters of reference indicate corresponding parts in all the figures.

25 My invention has relation to automatic car-couplings; and it consists in the improved construction and combination of parts of the same, as hereinafter more fully described and claimed.

30 In the accompanying drawings, the letter A indicates the draw-head provided with the coupling mechanism, and B the draw-head which receives the coupling-bolt, both of which heads may be attached to the cars in any suitable manner. The former head has a longitudinal recess, C, opening from the free end of the head and contracting toward the outer end, adapting it to receive and hold the shouldered end D of the coupling-bolt E, the outer 35 end of which forms a flat head, F, which is adapted to fit into the longitudinal recess G in the end of the draw-head which receives the coupling-pin, which recess is contracted at its outer end and flat at its aperture, so that 40 the flat head may be inserted with the head in a horizontal plane, when it may be turned to stand in a vertical plane, and the shoulders formed by the flat head will bear against the shoulders formed by the contracted recess. The face of the draw-head has an over-

hanging step or shoulder, H, above the opening of the recess, and the receiving draw-head has a similar step, I, the faces of which steps abut against each other, when the draw-heads are coupled and one side of the step upon the 55 receiving draw-head is cut off, forming a beveled shoulder, J, recessed a short distance from the surface of the step. A hook-shaped projection, K, projects below the opening of the recess upon the face of the coupling-head, 60 the inner end of the hook being immediately below the center of the recess, and it is adapted to receive a headed bar, L, projecting at a right angle from the coupling-bolt in the same plane as the flat head when it is desired to 65 have the said bolt drawn back, so as not to enter the receiving-head if accidentally coming in contact with it. Upon the one side of the coupling-head, at the side opposite to the side upon the receiving-head having the beveled shoulder, is secured a plate or flat bar, M, 70 having an oblique hinge, N, which causes the free end of the bar to swing over from one position to another at a right angle to the former, and the said bar has in or near its middle 75 a slot or perforation, O, into which slot the free shouldered end of a spring, P, fastened upon the under side of the step above the recess, catches when the plate or bar is swung out horizontally, while a similar shouldered 80 spring-catch, Q, fastened upon the under side of the draw-head, catches into the slot when the bar is swung down in its vertical position. A rod, R, projects from the outer edge of the flat bar, and a lever, S, the lower end, T, of 85 which is bifurcated, while its upper end, U, is bent rearward at a right angle, and bent downward at its outer end, and bears against a spring, V, with the upper end, is pivoted upon the outer edge of the bar, rocking in 90 the plane of the bar. The lower ends of the bifurcated lever are shouldered or notched, as shown at W, adapted to hold the laterally-projecting rod upon the coupling-bolt when it is to be held in position for coupling, and 95 the upper bent end of the lever bears when rocked against the upper end of a bar or rod, X, projecting upward from the catch upon the under side of the step, so that when the upper end of the lever is tilted rearward by the 100

beveled shoulder of the receiving-head when coupling, the rear end of the same will depress the spring-catch supporting the flat bar in its horizontal position, allowing it to drop 5 down.

In this manner it will be seen that when it is desired to couple the link or bolt is turned by its transverse rod into having the flat head in a horizontal plane, the flat bar is placed in 10 its horizontal position, and the bar upon the coupling-bolt is caught by the bifurcated shouldered ends of the lever, which will hold it until the receiving coupling-head comes in contact with its beveled shoulder with the 15 upper end of the lever, which releases the bar upon the coupling-bolt, which will drop, turning the same, the outer end of which has entered the recess of the receiving-head, so that the flat head will bear with its shoulders 20 against the shoulders of the recess, coupling the heads, the flat bar dropping down to the side, where the catch upon the under side of the draw-head will hold it.

If desired, the heads may be made double, 25 each head having two recesses, one holding the coupling-bolt and one receiving it from the head of the other car, so that each coupling is secured by two bolts, one from each head.

30 Having thus described my invention, I claim

and desire to secure by Letters Patent of the United States—

In a car-coupling, the combination of the coupling draw-head having longitudinal shouldered recess, the receiving draw-head 35 having shouldered recess, provided with a flat horizontal opening and the beveled shoulder, the coupling-bolt having shouldered inner end, laterally-projecting bar upon its shank, and flat shouldered head upon its outer end, 40 the obliquely-hinged flat bar, having a slot at its middle and a projecting bar at its outer edge, the spring-catches fastened upon the under side of the head and the step upon the face of the head, the latter having an upwardly-projecting bar, and the lever pivoted upon the outer edge of the flat bar having lower bifurcated shouldered ends, bearing with its 45 upper end against a spring, and having its upper end bent rearward and slightly downward at its outer end, all constructed to operate as and for the purpose shown and set forth.

In testimony that I claim the foregoing as my own I have hereunto affixed my signature in presence of two witnesses.

LARS GUSTAF HEDLUND.
